HERMETICALLY SEALED ELECTRO- MAGNETIC RELAY

Jack S. Hawkins, San Jose, Calif., assignor to Jennings
Radio Manufacturing Corporation, San Jose, Calif., a
corporation of Delaware

Filed Jan. 2, 1964, Ser. No. 78,025

Term of patent 14 years

(Cl. D26—13)

Fig 1

Fig 2

Fig 3

FIG. 1 is a perspective view of a hermetically sealed electromagnetic relay showing my new design;

FIG. 2 is an end elevational view of the relay as seen from the top of FIG. 1;

FIG. 3 is an end elevational view as seen from the bottom of FIG. 1;

FIG. 4 is a side elevational view as seen from the left side of FIG. 1;

FIG. 5 is a side elevational view as seen from the side of FIG. 1 farthest from the eye;

FIG. 6 is a side elevational view as seen from the right side of FIG. 1;

FIG. 7 is a side elevational view as seen from the side of FIG. 1 nearest the eye.

I claim:

The ornamental design for a hermetically sealed electromagnetic relay, as shown.
